ROBERT P. PRICE, OF BUTTE, MONTANA.

SWITCH-CLOSER.

1,282,937.

Specification of Letters Patent. Patented Oct. 29, 1918.

Application filed July 30, 1917. Serial No. 183,542.

To all whom it may concern:

Be it known that I, ROBERT P. PRICE, a citizen of the United States, residing at Butte, in the county of Silverbow and State 5 of Montana, have invented certain new and useful Improvements in Switch-Closers, of which the following is a specification.

This invention relates to an improved device for closing the switch commonly used 10 in connection with automobiles and closed when starting the engine and is of the same type disclosed in my prior application filed August 30th, 1916, Serial No. 117,757. The principal object of the invention is to so construct the device that the switch may not be 15 closed unless the proper combination is known and to further provide an improved type of abutment engaging finger so constructed that if the finger is brought into engagement with an abutment ring at any 20 point upon the circumference of the ring with the exception of that in which a cutout is formed, the finger will be extended thus preventing the abutment finger from passing 25 the ring.

Another object of the invention is to so construct this switch that the combination thereof may be readily changed when desired.

30 Another object of the invention is to so construct this switch that the locking finger will be normally held in a position to permit of passage through the ring when in alinement with the cutout thereof but to 35 prevent passage of the finger excepting at a predetermined point upon the ring.

Another object of the invention is to so construct this switch that it may be mounted upon the dash-board of the automobile where 40 it will be easy to have access to the switch.

This invention is illustrated in the accompanying drawings, wherein:—

Figure 1 is a vertical longitudinal sectional view through the improved switch. 45 Fig. 2 is a vertical transverse sectional view through the improved switch.

The cylinder 10 is connected with one side of the dash-board 11 and extends about an opening 12 in the dash-board. Slots 13 are 50 formed in the upper and lower portions of this cylinder and extend circumferentially of the same so that the permutation rings 14, 15 and 16 which are positioned in the cylinder may be releasably held in an adjusted position by means of the screw fasteners 17 extending through the slots 13.

These permutation rings are provided with notches or cutouts 18 and it will be seen that by turning the rings, the cutouts may be moved to adjusted position thus changing 60 the combination. Pins 21 extend from the ring 16 and constitute baffles which will make it more difficult for an unauthorized person to actuate this device.

A sleeve 22 extends through the opening 12 in the dash-board 11 and through an opening in the head 23 of the cylinder 10 and is rotatably mounted and held in place by means of the securing nut 24. This sleeve carries a head or knob 25 at its outer 70 end, which head is provided with a pointer or finger 26 extending across the dial 27 so that it can be readily ascertained when the sleeve has been turned to the proper position. A threaded stem 28 is rotatably 75 mounted in this sleeve and is provided at one end with a securing nut 29 and at its opposite end with a head or turning knob 30 which is similar to the turning knob 25 and is provided with an indicating finger 31 80 similar to the indicating fingers 26. It will thus be seen that the sleeve 22 and threaded stem 28 can be independently rotated and further that as the sleeve is provided with longitudinally extending slots 32, this sleeve 85 will form means for preventing rotation of the arm or finger 35 which is internally threaded and mounted upon this threaded stem 28 and extends through the slots 32 as clearly shown in Fig. 2. This finger will 90 therefore move longitudinally of the sleeve when the stem is rotated and during its course of movement will pass through the permutation rings 14, 15 and 16.

This finger is provided with a plunger 34 95 and with an engaging tooth 35, the plunger being slidably mounted in a pocket formed in the finger and yieldably held in a raised position as shown in Fig. 1 by means of the spring 36. When this finger 33 moves 100 to a point adjacent the dash-board, the tooth 35 will engage the movable contact 37 and move the same into engagement with the stationary contact 38 thus completing the circuit through the wires 39 and 40. In the 105 opposite end portion of the finger 33 there is provided a pocket in which is slidably mounted a plunger or tooth 41 secured between links 42 of the trigger lever 43. This trigger or lever 43 is pivotally connected 110 with the tooth or block 35 and is engaged by the spring 44 so that under normal condi-

tions the spring will move the trigger away from the plunger 34 and draw the plunger 41 upwardly to a point permitting it to pass through the permutation rings. If this trigger 43 should strike one of the permutation rings it will be moved toward the plunger 34 and the plunger 41 would then be moved downwardly so that its free end portion will engage the permutation rings thus preventing 5 the finger 33 from moving through the permutation rings. In the operation of this switch actuating device, the head 25 will be turned to move the indicating finger 26 to the proper position to bring the finger 33 into alinement with the notch of the permutation ring 16 and stem 28 will then be rotated through the medium of the head 30 thus causing the finger to move longitudinally of the stem and pass through the per- 10 mutation rings. The sleeve will then be turned to bring the finger into alinement with the notch of the ring 15 and after the stem 28 has been rotated to move the finger through the ring 15, the operation will be 15 repeated and the finger moved through the ring 14. A further turning of the stem 28 will bring the tooth 35 into engagement with the movable contact 37 and this contact will be brought into engagement with the sta- 20 tionary contact 38 thus closing the circuit. This can be easily done by a person know- 25 ing the proper combination but if an un- authorized person should attempt to move the finger longitudinally of the stem by ro- 30 tating the stem to bring the finger into en- gagement with the first permutation ring and then turning the sleeve so as to feel the combination, the trigger 43 would engage the ring 16 and move the plunger 41 out- 35 wardly into engagement with the ring thus preventing movement of the finger through the ring. The pins 21 would also tend to prevent movement of the sleeve 22 with the finger close to the ring. 40 45 When it is no longer necessary to have the circuit closed, the stem can be turned to the left thus moving the finger 33 toward the head 23 of the cylinder until the finger reaches the position shown in Fig. 1. It is not necessary to turn the sleeve to bring the finger into alinement with the notches of the permutation ring as the curved end face of this plunger 34 will permit the plunger to ride past the ring when moving to the inoperative position. A casing 45 is secured to the dash-board about the cylinder 10 thus inclosing the cylinder and preventing the combination from being tampered with and also protecting the device from injury due to dust and dirt. I have therefore provided a circuit closing device which is so constructed that it cannot be readily operated by unauthorized persons and which is so constructed that when so desired, the combination 50 55 60 65 65 may be readily and quickly changed.

This will prevent persons who at one time were authorized to operate the device from being able to operate the device when they no longer have the authority to do so.

Under normal conditions the outer ends 70 of the plunger 34 and trigger 43 project to a point so as to clear the notches 18 in the permutation rings when moved to register with the said notches. In any other position of these parts, they engage the 75 permutation rings. The outer end of the plunger 41 terminates so as to clear the permutation rings. If the finger 33 be advanced without first being moved to bring the plunger 34 and trigger 43 in line with 80 the notch 18 of the permutation ring, the outer end of the trigger 43 will engage with the permutation ring and be pressed backward, thereby projecting the plunger 41 across the path of the permutation ring to 85 be engaged thereby and prevent the finding of the notch by turning the sleeve 22. On the backward or reverse movement of the finger 33, its travel will not be obstructed if the plunger 34 and trigger 43 are not in 90 register with the notch 18 in the permutation ring, because the beveled end of the plunger 34 will ride on the permutation ring and the outer end of the trigger will move so as to likewise ride on the permuta- 95 tion ring. This movement of the trigger draws the plunger 41 inward.

What is claimed is:—

1. A permutation device comprising a cylinder, permutation rings in said cylinder, 100 a sleeve rotatably mounted to extend through the cylinder, and provided with longitudinally extending slots, a threaded stem extending through the sleeve, a finger positioned in the sleeve and provided with a threaded passage through which said stem passes whereby rotation of the stem will move the finger longitudinally, plungers 105 slidably connected with the finger, resilient means yieldably holding one of said plungers in an extended position, a trigger pivotally connected with the finger and engaging the second plunger for imparting movement thereto when the trigger is moved, and means engaging the trigger to yieldably 110 hold the same in a set position with the second plunger held out of engagement with the permutation ring.

2. A permutation device comprising a housing, and permutation rings in said 120 housing provided with passageways, a threaded stem rotatably mounted in said housing, a finger threaded upon said stem, a plunger slidably connected with the finger, a trigger pivotally connected with the finger 125 and provided with arms engaging the plunger, resilient means engaging the trigger to yieldably hold the trigger in a set position with the plunger out of position for engagement with the permutation rings, 130

engagement of the trigger with the permutation rings moving the plunger to an operative position, and means for rotating the threaded stem to move the finger longitudinally thereof.

3. A permutation device comprising a housing, permutation rings in said housing provided with passageways, a threaded stem extending through the housing and 10 rotatably mounted, a finger rotatably mounted upon the housing and moving longitudinally thereof when the stem is rotated, a plunger slidably connected with the finger, and actuating means carried by the 15 finger and connected with the plunger for moving the plunger to engage the permutation rings upon the actuating means coming in contact with the permutation rings.

4. A permutation device comprising a 20 housing, permutation rings in the housing, a threaded stem rotatably mounted in the

housing, a finger loose upon the stem and moving longitudinally thereof when the stem is rotated, a plunger slidably connected with the finger, and actuating means for the 25 plunger positioned to engage the permutation rings and move the plunger to an operative position.

5. A permutation device comprising a housing, permutation rings in the housing, 30 a finger movably mounted in the housing for passage through the permutation rings, plunger means movably connected with the finger and trigger means pivoted to the finger for moving the plunger means to an 35 operative position through engagement with the permutation rings.

In testimony whereof I affix my signature in presence of a witness.
